GIRDER FOR TIMBER BRIDGES

William K. Merridith, Sappho, Wash.

Application November 23, 1942, Serial No. 466,617

6 Claims. (Cl. 20—0.5)

This invention relates to girders adapted for use in many relations but more particularly applicable in the construction of timber bridges.

Broadly stated, the invention resides in providing a girder consisting of two long logs, one disposed above the other, with the larger or butt end of one log disposed toward the smaller end of the other log, together with novel means hereinafter described, for securing these logs together in such manner as to provide an exceedingly strong and rigid girder. Further objects and advantages of the invention will be set forth in the detailed description which follows.

In the accompanying drawings:

Fig. 1 is a side elevation of a girder constructed in accordance with the invention;

Fig. 2 is an end elevation looking from the right hand end of Fig. 1;

Fig. 3 is a plan view of the structure of Fig. 1;

Fig. 4 is a transverse sectional view upon line 4—4 of Fig. 1;

Fig. 5 is a fragmentary longitudinal sectional view through one of the key blocks hereinafter described.

Like numerals designate corresponding parts in all of the figures of the drawings.

In the drawings 5 designates the upper log and 6 the lower log of the girder. The invention, of course, is not restricted to logs of any particular size. However, in some sections of the country as, for example, in the Pacific Northwest it is possible to secure very long and large logs for the manufacture of girder units embodying the features of this invention. In carrying out the invention I have employed logs 112 feet in length with a thickness of 5 feet at the butt and 3 feet at the top or smaller end. By reversing the logs, as shown, not only is the girder made of uniform strength throughout its length but its upper and lower faces are caused to lie in substantial parallelism with each other. Transverse members 7, 8 and 9 constituting cap stays, spacing stays and bottom stays respectively are disposed at spaced intervals along the length of the girders and are tied together by vertical binding bolts 10 which lie outside of the logs but pass through the stays, as is clearly illustrated in Fig. 4. Wire rope ties 11 encircle the logs 5 and 6 and bind them together and against the spacing stays 8. At each end of the girder a wedge like end post 12—13 is shaped to engage a bevelled face 14 of log 5 and the upper face 15 of log 6. Since the disposition of these faces is such as to present, in effect, an outwardly flaring seat, it follows that when the end

posts are drawn forcibly inward they are caused to exert a wedging action between these surfaces. Since the stays 7 and 9, bolts 10 and wire wraps 11 prevent the logs from moving outwardly and away from each other, it follows that when the end posts are thus drawn into keyed relation to said logs the resultant structure is made so very rigid as to cause the girder to serve substantially as though it were made in one piece. When so braced a girder of this character will support an exceedingly heavy load. One girder of this type, of which I have knowledge, is handling a 200 ton locomotive and its loaded train with perfect safety. The means for drawing the end posts forcibly into the keyed relation described consists of long bolts or threaded rods 17 which pass through the lower log and through the end posts. Nuts threaded upon said rods act against wear plates 18. The girder may be utilized to support any suitable type of roadway. As illustrating one of these uses I have shown light stringers 19 supported upon the cap stays 7, said stringers, in turn, carrying cross ties 20 for the support of track rails 21.

It is to be understood that the invention is not limited to the precise construction set forth but that it includes within its purview whatever changes fairly come within either the terms or the spirit of the appended claims.

Having described my invention, what I claim is:

1. A girder comprising a pair of tapered, spaced logs reversed end for end with respect to each other and one being disposed over the other means disposed along the length of the girder for drawing said logs toward each other and resisting their separation, wedge like end posts engaging the ends of said logs, said end posts being so shaped as to exert a wedging action tending to thrust said logs apart, and means for exerting a drawing action upon said end posts to draw them forcibly inward to exert such wedging action.
2. A girder comprising a pair of tapered, spaced logs reversed in position with respect to each other so that the large end of one log lies opposite the small end of the other log and vice versa and one of said logs being disposed over the other, a plurality of upper cross stays disposed at spaced intervals along the top of the top log, a plurality of lower cross stays disposed beneath the lower log, binding rods for drawing the upper and lower stays forcibly toward each other, a wedge like post at the end of the girder,

one end of which engages a bevel end of one of the logs and the other end of which engages a side face of the other of said logs and means for drawing the end post forcibly toward said logs, to cause it to exert a wedging action between said logs.

3. A structure as recited in claim 2 wherein the drawing means comprises a threaded rod passing through the end post and through one only of said logs.

4. A structure as recited in claim 2 wherein said drawing means comprises a threaded rod passing through the end post and through the lowermost of said logs.

5. A structure of the character described comprising a pair of tapering logs having their butt ends reversed with respect to each other, one of said logs being disposed above the other, trans-

verse spacing stays between the said logs at spaced intervals therealong, transverse top and bottom stays aligned with the spacing stays, binding bolts passing vertically through said

5 stays outside of said logs and acting to draw the top and bottom stays into forcible engagement with said logs and to draw said logs into forcible engagement with the spacing stays, wire rope strands embracing the logs at spaced intervals along the length of the girder and wedge like end posts acting between said logs adjacent their ends.

6. A structure as recited in claim 5 in combination with means for drawing said end posts inwardly, said means comprising threaded rods passing through the posts and passing obliquely through one only of said logs.

WILLIAM K. MERRIDITH.
